UNITED STATES PATENT OFFICE.

WILLIAM F. HAUSSTEIN, OF LYNDHURST, NEW JERSEY, ASSIGNOR TO THE KEUFFEL & ESSER COMPANY, OF HOBOKEN, NEW JERSEY, A CORPORATION OF NEW JERSEY.

CALCULATING-MACHINE.

No. 882,680.

Specification of Letters Patent. Patented March 24, 1908.

Application filed November 22, 1904. Serial No. 233,884.

To all whom it may concern:

Be it known that I, WILLIAM F. HAUSSTEIN, a citizen of the United States, residing at Lyndhurst, in the county of Bergen and 5 State of New Jersey, have invented certain new and useful Improvements in Calculating-Machines, of which the following is a specification.

This invention relates to calculating machines, such as that which forms the subject matter of U. S. patent to Alexander Rechnitzer, Number 809,075, granted Jan. 2, 1906. In that machine, as is usual in many other calculating machines, there is provided 15 a series of indicating numeral wheels on a common shaft and means for returning all of these numeral wheels to their initial or zero positions. In this particular machine, the mechanism for this purpose is manually operated in both directions, and there are no means provided to prevent the continuation 20 of the movement beyond the position necessary to be attained to bring the numeral wheels to the zero position which position is also the proper one from which to begin any calculating operation.

It is the object of the present invention to provide such and similar zero-resetting mechanism with improved means for limiting the 30 movement in the direction for resetting the numeral wheels to the position which brings the wheels to zero, and for automatically returning the manual operating devices to their initial positions ready for another resetting 35 operation.

In the accompanying drawing in which is illustrated the present invention, together with so much of the original machine as is necessary to a proper understanding of its 40 construction and operation, Figure 1 is a plan view of two of the numeral wheels (the balance of the series being broken away) and the means for resetting them to zero position. Fig. 2 is a vertical sectional view on 45 the plane of the broken line 2—2 of Fig. 1, looking to the left as indicated by the arrow.

Fig. 3 is a vertical sectional view on a plane at right angles to that of Fig. 2. Fig. 4 is a horizontal sectional view on a plane cutting 50 through the vertical or barrel shaft above the pawl-yoke or wish-bone pawl, the barrel being sectioned on another plane, from the cam, the parts being in their initial positions, and Fig. 5 is a somewhat similar view, the parts

being in the positions assumed at the end of 55 the manual, zero-setting stroke or movement.

In the original machine there is a series of numeral wheels or disks of any desired number to suit the capacity of the machines, of which only two are shown here, marked 6 60 and 7, such series being loosely mounted on a shaft 8, and each numeral wheel having, secured thereto or formed integral therewith, a mutilated gear 9, part of its teeth being removed, or omitted, as at 10.

Parallel with the shaft 8 is a shaft 11 upon which are rigidly secured gears 12, as many as there are numeral wheels in the series, each of said gears being also mutilated by having part of its teeth omitted, or removed, as at 13, such shaft 11 being connected, by suitable bevel-gear, as at 14, with a vertical shaft 15, reaching through the top plate 16 and provided with a crank-handle 17 for manual operation. Below the plate 16 the 75 shaft 15 is incased in a fixed barrel 18 and a coiled spring 19 is located in said barrel, around the shaft, its inner end at 20 being secured to the shaft and its outer end, at 21 being secured to the barrel, so that the tension of the spring will always tend to unwind 80 itself from around the shaft and turn the shaft to the right, or clock-wise. This rotation of the shaft under the action of the spring is limited, so that the shaft must always stop in a position to bring the gears 12 into place with their mutilated parts 13 opposite the numeral wheels, as best shown in Figs. 2 and 4, in the former of which the gears are shown in this position while in the 90 latter the spring, barrel and shaft are similarly shown, such position being the initial or zero position of these parts.

Upon the shaft 15 is secured a disk 22 provided with diametrically opposite stop-teeth 23 and 24, the former having a radial face 25 and beveled face 26 and the latter a radial face 27 and a beveled face 28, the radial face 25 facing to the right and the radial face 27 to the left.

Pivoted to the casing is a double armed U-shaped or wish-bone pawl 29 whose arms 30 and 31 embrace yoke fashion the toothed disk 22 and have their extremities at a distance apart slightly less than the combined diameter of the disk and length of the teeth 23 and 24 so that when the extremity of one arm rests against the radial face of one tooth,

The other arm will rest on the outside of the opposite tooth, as shown in Figs. 4 and 5, one tooth always serving as a cam to press the arm of the yoke outward and cause the radial face of the other tooth to abut against the end of the opposite arm. The shaft being impelled toward the right by its spring, the tooth 23 is so positioned or timed that it will abut against the end of the arm 29 just when the mutilated portions 13 of the gears 12 are opposite to the gears 9 of the numeral wheels, all of the mutilated portions 13 being in line with each other. When the numeral wheels are at zero, the mutilated portions 10 of the gears 9 are opposite the mutilated portions of the gears 12, as shown in Fig. 2, and the rotation of the gears 12 will have no effect on the gears 9 or the numeral wheels and vice versa, the rotation of the numeral wheels and their gears 9 will have no effect on the gears 12.

In the operation of the machine, however, the numeral wheels are turned out of their zero positions to indicate various numbers, and when the operation is finished some or all of the gears 9 are turned to various positions. It may be that each one will be at a different distance from the zero position and no matter what these positions may be, a gear of each of the wheels 9 which has been turned from the zero position will be opposite the mutilated portion 13 of a gear 12. By now turning the handle 17 in the direction opposite to the stress of the spring, for instance to the left from the position of Fig. 4, the teeth of the gears 12 are brought into mesh with those of the gears 9 and the latter will be turned until their mutilated portions come opposite the gears 12 when the turning of the gears 9 will cease, and the rotation of the gears 12 one complete revolution will bring all of the gears 9 into this initial or zero position (Fig. 2).

During the revolution of the gears 12, the toothed disk 22 is turned, during the first half revolution of which turning, the beveled face 26 of the tooth 23 will slide inside of the arm 30 of the yoke-pawl 29 pressing that arm outward and the arm 31 inward; and during the second half revolution, the same beveled face 26 of the tooth 23 will press the arm 31 outward, drawing the arm 30 inward in the path of the tooth 24 thus causing its radial face 28 to abut against the end of the arm 30, (as in Fig. 5) and arresting the movement of the gears 12 at the end of one revolution. The whole series of gears 9 and 12 being now in position not to mesh with each other, the release of the manual stress upon the handle will permit the spring 19 to come into play and return the gears 12 and disk 22 to the position of Fig. 4 without disturbing the gears 9 or their numeral wheels, the action of the teeth 23 and 24 on the yoke 29 being the reverse of that before described.

What I claim as new is:—

1. The combination in a calculating machine of a shaft, a series of numeral wheels mounted loosely thereon, a parallel shaft provided with means for returning all of the 70 numeral wheels to the zero position said shaft being manually actuated in one direction and automatically returned, a disk rotating with said parallel shaft, and means coacting with said disk for limiting the rotation of said parallel shaft to one revolution in either direction.

2. The combination in a calculating machine of a shaft, a series of numeral wheels mounted loosely thereon, a parallel shaft 80 provided with means for returning all of the numeral wheels to the zero position said shaft being manually actuated in one direction and automatically returned, a disk rotating with said parallel shaft, and having 85 oppositely located teeth, and a yoke pawl embracing said disk and limiting the rotation of said parallel shaft to one revolution in either direction.

3. The combination in a calculating machine of a shaft, a series of numeral wheels mounted loosely thereon each being provided with a gear mutilated by the removal or omission of its teeth at one point, a parallel shaft, a series of gears rigidly secured 95 thereon in numbers equal to those of the numeral wheels and similarly mutilated, such mutilations in the gears of the parallel shaft being in line with each other, a spring for actuating said parallel shaft in one direction, 100 manual means for actuating it in the opposite direction, a disk rotating with said parallel shaft and having oppositely located teeth, and a yoke pawl embracing said disk and limiting the rotation of the parallel shaft 105 to one revolution in either direction.

4. The combination in a calculating machine, of a shaft, a series of numeral wheels mounted loosely thereon each being provided with a gear mutilated by the removal 110 or omission of its teeth at one point, a parallel shaft, a series of gears in number equal to those of the numeral wheels rigidly secured thereon and similarly mutilated, such mutilations being in line with each other in all the 115 gears of the latter series, a vertical shaft, gearing connecting it with said parallel shaft, a spring for actuating said vertical shaft in one direction, manual means for operating it in the opposite direction, and automatic means for limiting the rotation in either direction to one revolution.

5. The combination in a calculating machine, of a shaft, a series of numeral wheels mounted loosely thereon each being provided with a gear mutilated by the removal or omission of its teeth at one point, a parallel shaft, a series of gears in number equal to those of the numeral wheels rigidly secured 125 thereon and similarly mutilated, such mutil-

lations being in line with each other in all the gears of the latter series, a vertical shaft, gearing connecting it with said parallel shaft, a spring for actuating said vertical shaft in 5 one direction, manual means for actuating it in the opposite direction, a disk on the vertical shaft having oppositely located teeth, and a yoke-pawl embracing said disk and

limiting the rotation of said vertical shaft to one revolution in either direction. 10

In testimony whereof I affix my signature in presence of two witnesses.
